US00D908610S

(12) **United States Design Patent** (10) **Patent No.:** **US D908,610 S**
(45) **Date of Patent:** **** Jan. 26, 2021**

(54) **EXTERNAL BATTERY**

(71) Applicant: **Samsung Electronics Co., Ltd.**,
Suwon-si (KR)

(72) Inventors: **Sangsun Woo**, Suwon-si (KR); **Siyeon Lee**, Suwon-si (KR); **Hyemin Bae**, Suwon-si (KR)

(73) Assignee: **Samsung Electronics Co., Ltd.**,
Suwon-si (KR)

(**) Term: **15 Years**

(21) Appl. No.: **29/699,040**

(22) Filed: **Jul. 23, 2019**

(30) **Foreign Application Priority Data**

Jan. 31, 2019 (KR) 30-2019-0004990

(51) **LOC (13) Cl.** **13-02**

(52) **U.S. Cl.**

USPC **D13/103**; D13/108

(58) **Field of Classification Search**

USPC D13/103-108, 118-119, 184, 199;

D14/356, 432

(57) **CLAIM**

The ornamental design for an external battery, as shown and described.

DESCRIPTION

FIG. 1 is a front perspective view of an external battery showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is a rear perspective view thereof.

The broken lines in the figures depict portions of the external battery that form no part of the claimed design.

1 Claim, 8 Drawing Sheets
